DESCRIPTION

U.S. PATENT DOCUMENTS

The single FIGURE is the bottom plan view of a soleplate for laundry iron, showing my new design.

D330,965 S * 11/1992 Paulin D32/71
D441,157 S * 4/2001 Powell D32/71

The surfaces of the soleplate not shown in the drawing have been omitted because they are unornamented and their appearance is not claimed.
